UNITED STATES PATENT OFFICE.

MAX RUMPF, OF CHICAGO, ILLINOIS.

SELF-INKING HAND STAMP.

Application filed July 17, 1922. Serial No. 575,445.

To all whom it may concern:

Be it known that I, MAX RUMPF, a citizen of the United States, residing in the city of Chicago, in the county of Cook and the State of Illinois, have invented certain new and useful Improvements in Self-Inking Hand Stamps, of which the following is a specification, reference being had to the accompanying drawings, forming a part 10 thereof.

The purpose of this invention is to provide an improved construction of a hand operated stamp bearing a plurality of printing elements, and adapted to be adjusted 15 to bring any selected printing face into printing position, the specific purposes of the invention being to provide improved means for selecting and setting at the printing position the desired printing face, and 20 improved means for inking the stamp in the initial depression, and withdrawing the inking pad out of the path of descent of the stamp without wiping or dragging motion upon the stamp. It consists in the 25 elements and features of construction shown and described, as indicated in the claims.

In the drawings:—

Figure 1 is a front elevation of the hand stamping device embodying this invention.

Figure 2 is a right hand side or operating side elevation of the same.

Figure 3 is a section at the line, 3—3, on Figure 2.

Figure 4 is a section at the line, 4—4, on Figure 3, showing all parts in the position of rest.

Figure 5 is a left hand side elevation of the stamp showing the stamp-carrying rotor depressed sufficiently for bringing the stamping printing face in contact with the inking pad, in position of use with all parts at rest.

Figure 6 is a similar view showing the plunger and rotor further depressed while the stamp remains in inking contact with the pad, the pad carrier being depressed at the same time.

Figure 7 is a similar view showing the stamp carrying rotor further depressed and the inking pad depressed more than the rotor for clearing inking pad away from the printing face by direct movement.

Figure 8 is a similar view showing the stamp fully depressed, the inking pad

swung aside and the printing face in printing position.

Figure 9 is a detail assembled view of the levers and their supports by which the action of the inking pad is controlled.

Figure 10 is a dissected view of the parts 60 shown in Figure 9, showing each part in elevation.

The structure shown in the drawings comprises a frame or supporting structure consisting of end standards, 1, 1, cross-head, 1^a, 65 a plunger comprising side arms, 2, 2, cross-head, 2^a, and a stem, 2^b, which is provided at the upper end with an operating handle, 2^c. The cross-head, 1^a, of the stem has a boss, 1^c, constituting a guide bearing for 70 a stem, 2^b, of the plunger.

In the lower ends of the plunger arms, 2, 2, there is journaled a shaft, 5, for a rotor stamp carrier, 6 which is mounted on said shaft, 5, rigid therewith between the two 75 arms of the plunger; and said shaft is extended beyond said arms forming trunnions, 5^a, 5^b, which afford guidance for the plunger in the standard, being extended out through the said standards, 1, 1, which are vertically slotted as seen at 1^a for that purpose.

The ink pad carrier is provided with side arms, 7, 7, connected by a cross bar, 7^a. Said ink pad carrier is mounted upon the shaft, 5, for pivotal action there-about, having limited means of lost motion vertically with respect thereto by means of the elongation of the apertures, 7^b, 7^c, by which it is thus pivotally hung on the shaft.

The ink pad carrier is controlled in its 90 position and movement by levers, 8 and 9, which are both pivoted at their upper outer ends on an arm 1^b, extending rigidly rearward from the standard, 1. The construction comprising said levers, 8 and 9, and said 95 supporting arm, 1^b, being duplicated at both ends of the rotor, that is, adjacent and with respect to both standards, 1, 1. The arms, 1^b, project, as stated, from the standards, 1, 1, respectively, at a position in the height of 100 said standards for locating the pivotal connection of the levers, 8 and 9, somewhat above the level of the shaft, 5, at the highest position of said shaft, so that said levers trend downwardly and forwardly for their 105 co-operation with the plunger and with the ink pad carrier. Said co-operation with the pad carrier is effected by means of headed

studs, 7^c, constituting abutments projecting from the side arms, 7, 7, respectively, below and above said levers, 8 and 9, respectively, and with the plunger, by the trunnions or 5 projecting portions of the shaft, 5, and collars, 5^a, thereon, constituting and herein-after referred to as "abutments" on the plunger, said levers both extending below said abutments, 5^a, the abutments, 7^c, being 10 between the two levers as above indicated. The two levers, 8 and 9, are connected for their proper co-operation by means of a third lever, 10, fulcrumed at 10^a, upon the side arm, 1, (the construction being duplicated both sides of the plunger,) and has its free end extended in the cam head, 10^b, which bears upon a stud, 8^a, projecting laterally from the lever, 8; and a spring, 11, connected at its lower end to the lever, 9, 15 and at its upper end to a laterally projecting stud, 10^c, midway in the length of said third lever, 10, operates for stressing the lever, 9, toward the lever, 10, which, in view of the stoppage of the free end of the lever, 9, 20 against the abutment, 8^a, on the side arm of the ink pad carrier, tends to hold the lever, 10, pulled downwardly and the cross-head cam member, 10^b, pressed upon the laterally projecting abutment, 8^a, of the lever, 8; and 25 the lever, 10, and the levers, 8 and 9, are all pivoted to the same part, namely, the standard, 1. The total effect of the entire organization consisting of the levers, 8, 9 and 10, and the connecting spring, 11, is that the 30 spring reacting at one end through the lever, 10, and lever, 8, stopped at its free end against the plunger abutment, 5^a, and at the other end reacting on the lever, 9, to press the free end of said lever, 9, against the pad carrier abutment, 7^c, operates to press the 35 ink pad carrier up to the limit which is determined by the depth—upwardly—of a notch, 16, formed as a guideway in a plate, 17, mounted on the inner side of each standard, 1, for engaging guide-and-stop projections, 15, fixed on the lower ends of the pad carrier side arms, 7.

By the same spring means and lever connections, described, the plunger is upheld to 40 the upper limit, which is fixed by the upper end of the elongated pivot slots, 7^b, in the pad carrier side arms, 7, being reached by the trunnions, 5^a, on which the pad carrier is connected with the plunger. The result 45 of this construction, it will be seen, is that the plunger is upheld so as to space the printing face of the stamp above the inking face of the ink pad a distance which may be the amount of elongation of said pivot slots, 50 7^b; and to space the lower edge of the lever, 8, above the pad carrier abutment, 7^c, a similar distance (see Figure 9). And the 55 purpose, it will be understood, is to cause the pad carrier to continue to be upheld to 60 the position indicated while the plunger is

depressed the amount of the spacing stated to bring the printing face into inking contact with the pad.

The parts mentioned are in detail further formed so that during a further depression 70 of the plunger after the stamp face is in inking contact with the pad, the pad and the plunger are depressed together for a short distance adequate for insuring the transference of ink from the pad to the printing 75 face. In order that after this inking contact has been obtained the printing face and the inking surface may be separated by direct withdrawal of the one from the other before the lateral swing of the pad for taking it out of the path of the plunger is performed,—avoiding dragging the pad over the printing face and smearing the latter,—the upper edge of the end portion of the lever, 8, which is engaged under the plunger abutment is formed sloping relatively upward 80 and away from the lever fulcrum adapting said portion to operate as a cam against the plunger abutment, 5^a, in the lateral movement of said lever which results from the 85 downward movement of the plunger and of the lower edge of said lever, 8, to force the pad carrier abutment, 7^c, down faster than the plunger is descending, thus effecting the 90 desired direct separation of the pad from 95 the stamp face.

This action continues until by the lateral swing of the levers, 8 and 9, the hook terminals, 8^b and 9^b, of said levers reach the pad carrier abutment, 7^c. During the depression 100 of the plunger to this point the ink pad carrier is held to a vertical course and prevented from swinging laterally by engagement, as above described, of the projections, 15, at the lower end of the pad carrier side arms in the 105 guideways, 16, formed in guide plates, 17, mounted upon the inner side of the standards, 1, 1, respectively; and the said projections, 15, reach the end of said guideway and are in position to pass out of it laterally, 110 when the abutments, 7^c, encounter the hook terminals, 8^b and 9^b; and further depression of the plunger causes said terminals to swing the pad carrier aside, taking the guide projections, 15, out of the guideways, 17, and 115 clearing the path of the stamp to printing position, as seen in Figure 7.

The stamp carrier, 6, is a rotor, as stated, mounted upon the shaft, 5, for rotating thereabout, said rotor having a multiplicity of 120 paraxial seats or faces, adapted each for carrying a stamp, so that when the stamps are thus mounted upon the rotor, the rotor has a multiplicity of paraxial printing faces. The means are herein-after described, serving to rock the rotor, to cause it to present any selected printing face or seat for a printing stamp as the lower side, that is, positioned to be advanced or pressed downward upon the 125 paper for printing. The rotor stamp car- 130

rier, 6, is constructed in all respects substantially as shown and described in patent of myself and W. E. Nimz, No. 1,356,172, dated October 19, 1920, and this construction need 5 not be further described here.

The means for adjusting the rotor stamp carrier to bring any desired stamp at printing position and for indicating that printing position without operation of the stamp for 10 printing, as would be necessary in the absence of any special provision, because the stamp is concealed by the ink pad and cannot be examined directly, constitute an important feature of this invention and so far 15 as the device is in this respect different from that of said Patent No. 1,356,172, it will be now described.

The shaft, 5, is provided at the right hand end with a crank handle, 25; back of said 20 crank handle there is mounted rigid with the standard, 1, and spaced away therefrom, a notched disk, 26, having in its periphery as many equally spaced notches 26^a as there are stamp-carrying faces on the rotor. The 25 crank handle has its radially extending arm or lever double,—that is, comprising two parts, 27^a and 27^b, the former rigid with the shaft, 5, and the latter engaged with the shaft and with the bar, 27^a, below the shaft 30 at a stud, 27^c, and provided at its upper end with the operating handle, 25, and with a tooth, 28, for engaging the notches 26^a of the disk, 26, that tooth being formed by a 35 projection which is bent inward from the arm, 27^b, over the end of the arm, 27^a, which is notched at the end as seen at 27^c, for engaging the projection and preserving the two arms in alignment, and at the inner side of the arm, 27^b, this tooth is bent inward radially forming a hook which overhangs the 40 periphery of the notched disk and is adapted to be engaged with the notches by the reaction of the spring, 20, which tends to separate the two lever arms and retract the hook 45 outwardly. The operator will press the knob or operating handle, 27, inwardly for disengaging the tooth from the notches, preparatory to swinging the lever around the disk for a different engagement. A stop 50 stud, 26^d, projects from the outer side of the disk for encounter of the arm, 27^a, at which may be called the zero or no-stamp position, if one of the stamp holding faces of the rotor 55 is left empty, or to the position of the most usually used stamp to be mounted upon this face. By this means it will be seen that the rotor stamp carrier can be adjusted to bring any desired space at printing position.

In order to indicate to the operator what 60 stamp is at printing position, there is provided an index panel, 30, in the form of a segment of a cylinder about the rotor axis, which is mounted by a radial arm, 31, on the shaft of the 65 rotor, and is held in fixed position by means

of the spring finger, 30^a, having a pin, 30^b, which engages an aperture, 2^x, in the cross bar, 2^a, of the plunger which carries the rotor. This segment extends over the upper forward quarter of the rotor and carries an index sheet preferably removable so as to be interchangeable from time to time, containing a list of the several stamps carried by the rotor, one line being allotted to each stamp title, as seen clearly in Fig. 1. 70 For co-operating with the quadrant or segment index, 30, there is provided an index finger, 32^a, which projects off laterally from a radial arm, 32, of a gear segment, 33, which is mounted for rotation on and about the 75 shaft, 5, at the left hand side of the rotor, the finger 32^a, overhanging the index panel at the left hand margin thereof, as seen clearly in Figure 1. For operating the index finger to cause it to move over the index 80 panel, 30, from line to line thereof, as the rotor is turned from stamp-carrying face to stamp-carrying face, there is provided, fast on the shaft, 5, a gear pinion, 35, which meshes with the peripheral gear teeth, 37, of the double gear segment member, 38, which is pivoted to the left hand side bar of the rotor-carrying plunger, at 39, preferably, as shown, in vertical line with the axis of the shaft, 5. An interior gear, 40, on this 85 segment meshes with the teeth of the gear segment, 33, which has the index finger, 32^a, above described. The dimensions of the several co-operating gear members, to-wit,— 90 the pinion, 35, the gear segment, 37, the gear segment, 40, and the gear segment, 33, are calculated to cause that the rotation of the shaft, 5, by rotation of the crank handle, 25, from one side to the other of stop stud, 27, shall rock the index finger from registration 95 with the top line to registration with the bottom line of the index, the notches in the disk, 26, being positioned to engage the crank handle at the position of registration 100 of the index finger with the index lines respectively.

For convenience of inserting and securing the ink pad on the pad carrier, the pad holding pan, 70, which is dimensioned for seating on the cross-bar, 7, of the pad carrier, 115 has a laterally projecting handle, 71, to which there is pivoted at 71^a a latch member, 72, which extends under the bar, 7, and has an upwardly projecting stud or finger, 73, which engages the aperture, 74, in said bar, 120 7. The latch member has an extension, 75, constituting a handle opposed to the handle, 71; and a spring, 76, interposed between the two handles reacts for holding the finger, 73, engaged in the aperture, 74, when the 125 pad had been seated at correct position on the bar, 7. It will be understood that the operator, grasping the two handles and pressing them together may disengage the finger, 73, from the aperture, 74, and with- 130

draw the ink pad bodily from the bar, 7, and similarly holding the handles pressed together while entering the pan above the cross-bar he will release the handles and 5 slide the pan in until the finger snaps into the aperture.

I claim:

1. In combination with a frame and a stamp carrying plunger mounted for reciprocation therein, an ink pad carrier suspended from the plunger pivotally for swinging laterally out from below the stamp-carrying end of the plunger, with a short vertical range of lost motion at its pivot; a lever 10 having its fulcrum on the standard at a distance laterally off from the vertical path of reciprocation of the plunger, and extending down inwardly alongside the suspending arms of the pad carrier, the latter having an abutment above which the free end of the lever extends, the plunger having an abutment below which the lever extends, spring-pressed means yieldingly upholding the lever against the abutment above, and 15 connections from said spring-pressed means 20 connections from said spring-pressed means engaging the pad carrier to uphold it.

2. In a device for the purpose indicated, in combination with a frame and a stamp-carrying plunger mounted for reciprocation therein; a yieldingly upheld ink-pad-carrier suspended from the plunger pivotally for swinging laterally out from below the stamp on the plunger with a short vertical range of lost motion at its pivot; a lever 25 having its fulcrum pivot on the standard at a distance laterally off from the vertical path of reciprocation of the plunger, and extending thence downward and inward alongside the suspending arm of the ink pad 30 carrier, the plunger having an abutment below which the lever extends, and the ink pad carrier having an abutment above which the lever extends; spring means yieldingly upholding the lever against the plunger 35 abutment for upholding the plunger; means for stopping the pad carrier upwardly at a position at which its said abutment is spaced below said lever a distance for spacing the stamp face away from the inking pad prior 40 to the initial descending movement of the plunger.

3. In the construction defined in claim 1, foregoing, the end portion of the lever which is spring-pressed against the plunger abutment being formed as a cam having its edge 45 which encounters the abutment trending upwardly and away from the lever fulcrum, outwardly from the point of encounter with the plunger abutment at undepressed position of the plunger, for causing the lever to force the pad carrier abutment downward at the portion of the depression of the plunger faster than the plunger is depressed, for withdrawing the pad from the printing 50 face of the stamp.

4. In the construction defined in claim 1, foregoing, the lever having a hook for engaging the pad carrier abutment after a limited lateral swing of the lever, to swing the pad carrier laterally out from under the 55 plunger during the latter part of the plunger's descent.

5. In the construction defined in claim 1, foregoing, connections for upholding the pad carrier comprising a second lever fulcrumed approximately to the first lever, engaging by its free end the pad carrier abutment and spring-pressed upwardly, said lever having a hook for engaging the pad carrier abutment after a limited lateral 60 swing of the lever, to swing the pad carrier laterally out from under the plunger during the later part of the plunger's descent, the cam edge of the lever link being formed toward its outer extremity for substantially 65 vertical position at the laterally out-swung position of the lever link for holding the pad out of the plunger's path.

6. In the construction defined in claim 1, foregoing, connections for upholding the pad carrier comprising a second lever fulcrumed approximately to the first lever, engaging by its free end the pad carrier abutment and spring-pressed upwardly, said lever having a hook for engaging the pad carrier abutment at the limited lateral swing of the lever to swing the pad carrier laterally out from under the plunger during the later part of the plunger's descent; co-operating guide means on the standard and pad carrier for keeping the pad carrier in a vertical path during the movement for inking the stamp and withdrawing the pad from the stamp, said guide means being cut away 100 for escape of said co-operating guide means from each other at the point in the descent at which the hook of the lever link encounters the abutment of the pad carrier.

7. In the construction defined in claim 1, foregoing, the means for yieldingly upholding the pad carrier, being a lever fulcrumed on the standard at one end and at the other end stopped against the previously mentioned lever, a third lever fulcrumed on the standard and extending under the pad carrier abutment, and a spring connecting the second and third levers between their ends.

8. In the construction defined in claim 1, foregoing, the means for yieldingly upholding the lever mentioned against the plunger abutment, being an additional lever fulcrumed on the standard and extended from its fulcrum in a direction terminating at a position for swinging its said terminal inward, toward the path of reciprocation of the plunger abutment, by the downward swinging of said additional lever about its fulcrum; and a spring connected to said additional lever for so swinging it, the first lever mentioned having an abutment 115 position of the plunger, for causing the lever to force the pad carrier abutment downward at the portion of the depression of the plunger faster than the plunger is depressed, for withdrawing the pad from the printing 120 face of the stamp.

tioned for encounter with the end of said additional lever in such swinging of the latter.

9. In a self-inking stamp, in combination with a frame and a stamp carrying plunger mounted for reciprocation therein; an ink pad carrier suspended from the plunger with limited vertical range of lost motion at its point of suspension; spring means for yieldingly upholding the pad carrier; a stop on the frame for limiting the upward movement of the pad carrier at a position of the inking pad short of the printing face of the stamp on the plunger; a lever pivoted on the frame at a distance laterally from the path of reciprocation of the plunger abutment and above the level of the highest position of said abutment, spring pressed upwardly against said abutment for yieldingly upholding the plunger out of contact of the printing face with the inking pad, the inking pad carrier having an abutment projecting into the path of the downward swing of the lever spaced therefrom when the lever is in contact with the plunger abutment a predetermined distance corresponding to the clearance between the printing face of the stamp and the inking pad at the undepressed position of both.
10. In the construction defined in claim 9 foregoing, said lever having its end portion which makes contact with the plunger abutment formed as to its upper edge to constitute a cam up-raise or vertical widening of said end portion, whereby the lateral swinging movement of the lever which accompanies its down swinging, draws said cam or widened end portion between the plunger abutment and the pad carrier abutment, and depresses the pad carrier away from the printing face of the stamp on the plunger.
11. In the construction defined in claim 9, foregoing, the lever being terminated by a hook member which engages the plunger abutment laterally after a limited lateral swinging movement which accompanies the down swinging movement of the lever; whereby the continued depression of the lever by the plunger causes said lever to

swing the pad carrier laterally out from under the plunger.

12. In the construction defined in claim 9, foregoing, the means for yieldingly upholding the pad carrier, comprising a lever fulcrumed on the frame at a distance laterally from the path of reciprocation of the point of suspension of the pad carrier and engaging under the abutment of the pad carrier, and a spring reacting between said lever and the frame for upholding the free end of the lever, said lever having a terminal hook for encountering laterally the abutment on the pad carrier in the lateral swinging of said lever to accompany its downward swinging movement, whereby after a limited downward swinging of the lever and depression of the pad carrier, further depression of the pad carrier causes it to be swung laterally by said hook lever to take the pad out of the plunger.

13. In a self-inking pad, in combination with a frame and a plunger mounted for reciprocation therein, a rotor carried by the plunger having a multiplicity of paraxially extended faces, each adapted for having mounted thereon a printing stamp; means for rotatively adjusting the rotor about its axis on the plunger, an index panel mounted on the frame in fixed position; an index finger mounted on the frame for movement of its point over the panel; a gear on the rotor; a gear segment which carries the index finger, and gear means intermediate the gear and gear segment for giving the finger reduced angular movement in comparison with the gear on the rotor.

14. In the construction defined in claim 13, foregoing, the index panel being a segment of a cylinder about the rotor axis, the index-finger-carrying gear segment being mounted on the rotor shaft, and the intermediate gear element being a sector having two concentric gear segments meshing respectively with the gear and the gear segment on the rotor shaft.

In testimony whereof, I have hereunto set my hand at Chicago, Illinois, this 14th day of July, 1922.

MAX RUMPF.
